UNITED STATES PATENT OFFICE.

JAMES H. BLESSING, OF ALBANY, NEW YORK.

STEAM-TRAP.

SPECIFICATION forming part of Letters Patent No. 341,548, dated May 11, 1886.

Application filed October 7, 1885. Serial No. 179,193. (No model.)

To all whom it may concern:

Be it known that I, JAMES H. BLESSING, of the city and county of Albany, in the State of New York, have invented new and useful Improvements in Steam-Traps, of which the following is a specification.

This invention relates to improvements upon the apparatus for which the following Letters Patent have heretofore been granted to me, to wit: No. 207,484, dated August 27, 1878, No. 234,386, November 16, 1880, and No. 268,384, December 5, 1882.

The objects of my present invention are, first, to adapt the apparatus for operating with a closed pressure steam-heating system where-in the steam-pressure in the pipes is maintained at a point greatly below that at which the pressure of it is carried in the boiler, and, second, to provide means for preventing an untimely closure (by a water seal) of the pipe leading from the inside of the bucket into the receiver placed outside of the trap. I attain these objects by means of the mechanism illustrated in the accompanying drawings, which are herein referred to, and form part of this specification.

In said drawings, Figure 1 is a vertical section of my trap with the bucket in its raised position; Fig. 2, a like section with the bucket in its depressed position; Fig. 3, a transverse vertical section of Fig. 2; Figs. 4 and 5, enlarged longitudinal sections of the casing for the inlet steam and exhaust valves, the first showing the steam-inlet valve closed and exhaust-valve opened, and the second showing the exhaust-valve closed, and the steam-inlet valve opened; and Fig. 6, a transverse section at the line $x-x$ of Fig. 4.

As represented in the drawings, A is the exterior case of the trap, and B the bucket contained therein. Said bucket is provided with a central sleeve, C, that is fitted to slide freely on a guide-rod, a, which extends from the bottom to the top of the casing A. The bucket B is formed to leave a small annular space between its exterior surface and the interior surface of the casing A. Condensed water from the heating-pipes is admitted into this annular space, and from thence into the bucket B by means of the inlet water-pipe D, as fully described and shown in my Patent No. 268,384, hereinbefore referred to. A siphon-pipe, E,

extends downward into the bucket B, and is connected by the discharge-pipe F so as to deliver the water from the trap into the boiler 55 below the water-line of the latter, as shown in Fig. 3.

The valve casing G, to which the equalizing steam-pipe from the steam-space of the boiler is connected, is attached to the upper part of 60 the casing A. Said valve-casing contains an inlet steam-valve, g, and an exhaust-valve, g', which are so arranged that as one is closed the other will be reciprocally opened. A bifurcated lever, H, that vibrates on a center, h, 65 (fixed between the valves g and g'), is adapted to loosely engage between the collars g² (on the stem of the valve g) and between the collar g³ on the stem of the valve g' and the upper face of the latter, the collar g³ being placed at such 70 distance from the upper face of the valve g' as to afford considerable lost motion to the lever H between said collar and valve, so as to produce but a slight lift to the exhaust-valve g', and so that by a slight falling movement of 75 the bucket B (by which the valve mechanism is operated) the exhaust-valve g' will be restored to its seat. Below the exhaust-valve g' an exhaust-opening, g', is made for permitting the steam confined in the trap to escape, 80 either into the atmosphere or, when preferred, into a pipe that is connected to the steam-heating pipes. The latter feature, which I reserve for a separate application for Letters Patent, is not represented in the drawings. 85 The inner end of the lever H engages between the collars c (formed on the sleeve C) in such manner that the rising and falling movements of the bucket B will produce corresponding vibrations of the lever H.

The receiver I is connected to the trap by two pipes. The upper pipe, i, passes into the trap through the cover of the casing A, and extends downward so as to reach nearly to the bottom of the bucket B when the latter is at 95 the highest point of its movement, as shown in Fig. 1. The lower pipe, i', leads from the bottom of the receiver I into the lower part of the casing A, and is provided with a check-valve that is arranged to prevent the water 100 in the lower part of the trap from passing up through the pipe i' into the receiver I. The part of the pipe i that passes into the bucket B is perforated, as shown in Fig. 1, and is

provided with a sliding sleeve, J, which is adapted to cover over and close the perforations in the pipe i, as shown in Fig. 2, when the bucket B is at the lowest point of its movement. The sleeve J is provided with two concentric flanges, j, between which the lug c' of the sleeve C engages, so as to correspondingly move the sleeve J on the pipe i with every movement of the bucket B.

10 It being understood that the trap is connected by its discharge-pipe, F to a steam-boiler in which the pressure is carried at a much higher point than in the system of heating-pipes, it is obvious that without some means for reducing in the trap the pressure that is required to return the water into the boiler, considerable time would be wasted after each discharge of the bucket before the pressure in the trap would be reduced by condensation 15 sufficiently low to permit the water in the system of heating-pipes to flow into the trap through the inlet water-pipe D, and it also being understood that when the bucket B is in its highest position with a little water in 20 its bottom a water-seal will be formed at the lower end of the pipe i, so as to prevent steam from passing up through the said pipe into the receiver I, unless some provision is made in said pipe for the admission of steam there- 25 into at some point above the lower end of the pipe. These provisions are made in my present improvement in steam-traps, whose operation is as follows: Supposing the bucket to have been just filled with water and to have 30 dropped to its lowest position, as shown in Fig. 2, thereby opening the inlet steam valve g to equalize the steam-pressure in the trap with that in the boiler, and closing the exhaust-valve g' and moving the sliding sleeve 35 J in a position to cover the perforations in the pipe i, everything is now in condition for the discharge of the water contained in the bucket B, and under the equalized pressure the water flows through the siphon-pipe 40 E and discharge-pipe F into the boiler, and at the same time a portion of the water will pass through the pipe i so as to nearly or quite fill the receiver I. While the water is being discharged from the bucket B, the latter will continue to rise, and by this rising 45 movement of the bucket the sleeve J will be raised to uncover the perforations in the pipe i, and the lever H will be tilted to close the steam-inlet valve g, and—a moment before the 50 bucket has reached the highest point of its movement—to slightly open the exhaust-valve g', and by this latter act the pressure in trap will be reduced to or a little below that in the steam-heating pipes, and from the latter the 55 water of condensation begins to flow into the trap, first filling the annular space between the bucket B and casing A, and then, by pouring over the upper edge of the bucket, filling 60

into the latter until the weight of the bucket and its contents overcomes the flotation of the 65 surrounding water, when the bucket will be suddenly sunk, and thereby permit a large portion of the water which surrounds the bucket to pass over into the bucket, and thereby augment the contents of the latter. The first slight 70 downward movement of the bucket tilts the inner end of the lever H, so as to permit the exhaust-valve g' to become seated some time before the steam-inlet valve g is raised from its seat. When the bucket has sunk to its 75 lowest position, the trap is in condition for the discharge of the water therefrom, as hereinbefore described. By the rising movement of the sliding sleeve J the perforations in the pipe i will be uncovered, thereby permitting 80 the pressure of the steam in the trap to pass up through said pipe into the receiver I, and causing the water in said receiver to pass down into the lower part of the casing A, so as to accelerate the upward movement of the 85 bucket B.

I claim as my invention—

1. An automatic steam-trap consisting of a close vessel containing an open-top bucket, adapted to rise and fall in said vessel, a steam-inlet valve and a steam-exhaust valve which are arranged to open and close reciprocally to each other, an inlet water-pipe, and a siphon discharge-pipe, whereby the water is removed from the said bucket, all substantially as herein specified. 95

2. In an automatic closed steam-trap, the combination, with an open-top bucket adapted to rise and fall in the closed containing-vessel, an inlet water-pipe, and a siphon discharge-pipe, whereby the water is carried out of the said bucket, of a steam-inlet valve, whereby the pressure in the trap is equalized with that in the supply-boiler, and a steam-exhaust valve, whereby the pressure in the trap is reduced before each admission of water into the trap, as herein described, the said steam-inlet valve and the steam-exhaust valve being arranged to operate so that when either is opened the other will be reciprocally closed, as and for the purpose specified. 105

3. In an automatic steam-trap, the combination, with a close containing-vessel having an open-top bucket adapted to rise and fall therein, of an auxiliary water-receiver having 115 one of its connecting-pipes reaching downward into said bucket, the said pipe being provided with lateral openings or perforations, and a sliding sleeve adapted to be moved up and down on said pipe by the rising and falling 120 movement of the bucket, as herein specified.

JAMES H. BLESSING.
